CARPET.

No. 15,540.

Patented Nov. 11, 1884.

UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 15,540, dated November 11, 1884.

Application filed September 6, 1884. Term of patent 3½ years.

To all whom it may concern:

Be it known that I, ARTHUR L. HALLIDAY, a resident of New York city, in the county and State of New York, have invented and produced a new and original Design for a Carpet, of which the following is a full description, in connection with the accompanying photograph, which represents a face view of my new design for a carpet.

10 This invention relates to a new ornamentation of the face of a carpet, oil-cloth, or analogous fabric; and it consists in the novel grouping and outlines of figures hereinafter described.

15 In the photograph, the letter A represents a large fanciful leaf with rosette-like borders and spear-shaped projecting ornaments a, said figure being connected with groups of rosettes B B. Between these groups of rosettes there 20 is another ornamental leaf, C, having fanciful projecting ornaments b.

Figures A B C a b are contained within the principal band or stripe of the carpet, said carpet having other bands, D, E, F, and G, as shown.

25

I claim—

1. The design for a carpet or other fabric, the same consisting of the figures A, a, and B, substantially as shown.

2. The design for a carpet or other fabric, the same consisting of the figures C and b, substantially as shown.

3. The design for a carpet or other fabric, the same consisting of the figures A, B, C, a, and b, substantially as shown.

35 4. The design for a carpet or other fabric, the same consisting of the figures A, B, C, a, b, D, E, F, and G, substantially as shown.

ARTHUR L. HALLIDAY.
